DESIGN FOR A DRESS

William Slepin, Philadelphia, Pa.

Application September 19, 1938, Serial No. 79,976

Term of patent 3½ years

To all whom it may concern:

Be it known that I, William Slepin, a citizen of the United States and residing in the city and county of Philadelphia, State of Pennsylvania, have invented a new, original, and ornamental Design for a Dress, of which the following is a specification, reference being had to the accompanying drawing, forming part thereof, wherein

Fig. 1 is the front view of a dress showing my new design.

Fig. 2 is a rear view thereof.

The characteristic feature of my design resides in the combination on the specific dress disclosed of the specific puffing on the front and rear blouse portions as shown.

I claim:

The ornamental design for a dress, substantially as shown and described.

WILLIAM SLEPIN.
